(57) **CLAIM**

The ornamental design for a pregnancy test device display panel with transitional graphical user interface, as shown.

DESCRIPTION

FIG. 1 is a top perspective view of a first image in a sequence of a pregnancy test device display panel with transitional graphical user interface, showing my new design;

FIG. 2 is a top plan view of the design shown in FIG. 1; FIG. 3 is a top perspective view of a second image in the sequence; and,

FIG. 4 is a top plan view of the design shown in FIG. 3. The appearance of the image sequentially transitions between the images shown in FIGS. 1 and 3. The process or period in which one image transitions to another forms no part of the claimed design.

The horizontal lines illustrate surface shading on the display panel. The broken line showing of a pregnancy test device illustrates the environment of the design and forms no part of the claimed design.

1 Claim, 4 Drawing Sheets
